UNITED STATES PATENT OFFICE.

THOMAS A. WESTON, OF ARDEN, NORTH CAROLINA.

SHUTTER STAY AND ADJUSTER.

No. 874,468.

Specification of Letters Patent.

Patented Dec. 24, 1907.

Application filed October 31, 1903. Serial No. 179,385.

To all whom it may concern:

Be it known that I, THOMAS A. WESTON, a citizen of the United States of America, residing in Arden, county of Buncombe, State of North Carolina, have invented certain Improvements in Shutter Stays or Adjusters, of which the following is a specification.

My invention relates to frictional shutter stays or adjusters of the class illustrated in the specification of my United States patent of December 26th, 1899, No. 640,057, its object being to further increase their efficiency and to extend their applicability, in particular to adapt them to the type of stays having a pivotal connection with the sill of the window for the controlling of a single shutter.

My invention is obviously also intended for the better adjustment in like manner of French windows, transoms, or other allied or hinged structures.

In the accompanying drawings Figure 1 is a plan view of my improved stay applied to a single shutter: Fig. 2 is a longitudinal elevation of the same partly in section: Fig. 3 is an elevation of the frictional bracket at right angles to Fig. 2: Fig. 4 is a central sectional view of the bracket showing the thumb screw withdrawn: Fig. 5 is a top plan view of the conical friction hub within the bracket: Fig. 5^a is a bottom view of the disk above the conical hub: Fig. 6 is a transverse sectional view on the line 6—6, Fig. 2: Figs. 7 and 8 are side elevation and plan respectively of the friction pivoted stay hook: and Figs. 9 and 9^a are horizontal and vertical sections of a modified stay hook.

My invention in its main parts comprises a frictional shutter bracket A secured to the single swinging shutter B, a sliding or telescoped two-part stay arm C, D, a frictional clamp E thereon concentric to the axis of the stay arm C, D, and a pivot pedestal E¹ secured to the sill of the window by one central screw G, and a loose pin or pivot connection, whereby the bracket end of the stay arm C, D, is pivoted to the rotatory friction hub or plug a¹ within the bracket A. The axial movement of the said plug combined with a possible movement when required of the stay arm in a plane at right angles upon the pivot a⁶, together afford to the stay arm perfect freedom from cramping or bending when the shutter is swung, and which otherwise might occur from the sagging of the shutter or from imperfect alinement in first attaching the bracket. In the bracket of my

aforesaid U. S. patent the sliding stay arm or bar is rigidly attached to its rotating frictional part at the said shutter bracket, whereby a cramping or bending action upon the stay bar is possible. A further advantage in the aforesaid detachable pivot connection of the stay arm or bar to the bracket, is the increased facility of first attaching the device to the shutter. The separate detached brackets are easy to handle and can be screwed to their places unencumbered by the stay bar. The sill pedestal E¹ requires but one screw to attach it immovably to the sill, the device as shown in the drawings being self-adapting to any slope or angle in the sill face without cutting the sill.

The concentric friction clamp E affords a convenient hand grip for pushing or pulling the attached shutter to and fro into the position desired, and by a slight rotatory movement thereto, all the connected parts may be at once firmly locked by friction in any position.

The pivoted hook H by friction at its pivot (hereinafter described) will remain elevated out of action and clear of the stay arm, so as to allow a very slightly bowed position of the shutters without interference from the hook end dragging upon the stay. The hook is also a convenient means wherewith to pull the shutter firmly closed, and there lock it by pushing the hook down over the stay arm.

The shutter bracket A is conically shaped within to fit upon the conical plug or hub a¹ for frictional engagement. The plug a¹ has a thumb screw a² threaded into it adapted to draw together the conical friction surfaces or to release them. A cap or collar a³ is engaged with the upper end of the plug a¹ by means of a rib or feather a⁴ upon cap a³ entering a groove or cross slot a⁵ in the plug end. The said rib and groove engagement insures simultaneous motion to both parts and prevents the unscrewing of the thumb screw by the swinging of the shutter. The lower end of the plug a¹ has a wide transverse slot a⁶ to receive the end of the tube C and retain it upon the pivot pin a⁶, upon which pin the tube C has a limited angular movement to avert the cramping of the moving parts, as explained hereinbefore. This improved form of frictional bracket with its hub or plug contrasted with the disk form of my aforesaid prior patent, provides a ready swiveled attachment to the stay bar by a simple pivot

pin affording a simple and inexpensive form of construction.

The sliding stay arm consists of an external tube C pivoted at the bracket end to the 5 plug a^1 and an inner tube or rod D pivoted to the pedestal E¹ on the sill by the screw G. The said sliding members C, D, may be frictionally locked to each other, when desired, by the clamp E. The end of the tube C carries 10 secured to it rigidly, a short sleeve e², having its outer end coned and its inner end threaded. An outer shell e¹ has its inner bore in like manner coned at one end and threaded at the other to correspond with and 15 fit respectively the cone end and threaded end of the sleeve e². Both the sleeve and contiguous inclosed tube end are cross slotted with slots e³ to allow of bending and contraction upon the inner tube D when the 20 shell e¹ is rotated so as by its screw threads to be drawn in a longitudinal direction to compress the said coned parts upon the tube D. The reverse rotation of the shell e¹ frees the tubes C, D from each other, so that they may 25 slide freely in order to lengthen or shorten them to locate the attached shutter where desired.

The shutter can be frictionally locked in any position either by the clamp E or by the 30 bracket thumb screw a^2 , but most effectively against movement by the wind, by the concurrent use of both frictions. It is intended that the frictional engagement of the parts should always be made less than sufficient to 35 resist a movement of the shutters by the strongest winds, so as to avoid the tearing of the shutters from their hinges in a hurricane, which can readily occur with the common unyielding positive shutter adjusters. My 40 frictional stays yield when necessary to dangerous winds. They do not clatter and make noises under any circumstances.

My improved sill pedestal is affixed by one screw G having just below its head a slight 45 shoulder g¹ to press on the ball shaped piece g² and force the same firmly into the orifice f¹ of the cup f². The lower open end f³ encircles snugly the washer or plate f⁴, which latter is fixed to the sill by nails or screws f⁵. 50 The spherical lower end of ball g² may occupy various positions in the orifice f¹ of the cup f², allowing the latter to adapt itself flat to the sill whatever its angle or 'slope', while the screw G stands vertical as a pivot to the stay

arm. The screw G secures the ball and cup 55 base solidly to the sill against all lateral strains which can then only bend the screw by first shearing the nails f⁵ in the washer.

My before mentioned shutter hook H is slotted lengthwise by a slot i¹ and the separated parts are sprung open a little before pivoting them within the base plate i². The slotted shank furnishes side friction within the base plate to hold the hook from falling, thus keeping its upward position clear of the 60 stay arm until pushed down over the latter.

In Figs. 9 and 9^a I have shown a shutter hook differing from that just described in the 65 length of frictional bearing obtained for the slotted shank.

70

I claim as my invention

1. A shutter stay having slidable stay rods, a friction bracket and two superposed pivoted connections at right angles to each other between said bracket and stay rods 75 whereby said parts have universal motion with relation to each other, substantially as described.

2. A shutter stay having slidable stay arms, a bracket, a plug adapted for frictional 80 action within aforesaid bracket, said plug being provided with a vertically slotted base adapted to receive the end of the stay arm and further provided with a pivot whereby the said stay arm and bracket are universally 85 jointed to each other.

3. A pivot pedestal for shutter stays and the like, having a base adapted to fit on any angle and a stationary pivot part adapted to occupy a vertical position irrespective of the 90 base, substantially as described.

4. A pivot pedestal for shutter stays and the like, comprising a cupped base having a central opening, a screw, a ball fitting the screw, said ball occupying a position in said 95 opening and said screw securing the base to the sill, substantially as described.

5. A pivot pedestal for shutter stays, comprising a disk secured to the sill, a cupped base embracing said disk and a central pivot 100 screw passing through the cup and disk.

In testimony whereof I have signed my name to this specification, in the presence of two subscribing witnesses.

THOS. A. WESTON.
